(57) **CLAIM**

The ornamental design for current sensor as shown and described.

DESCRIPTION

1. Current sensor

1.1 is an isometric view of a current sensor in accordance with the present invention;

1.2 is a side elevational view of a first side of the current sensor of 1.1;

1.3 is a top plan view of the current sensor of 1.1;

1.4 is a side elevational view of a second side of the current sensor of 1.1;

1.5 is a bottom plan view of the current sensor of 1.1; and

1.6 is a front elevational view of the current sensor of 1.1. The broken lines shown are included for the purpose of illustrating portions of the current sensor that form no part of the claim.
